UNITED STATES PATENT OFFICE.

AARON S. KATZ, OF NEW YORK, N. Y.

DESIGN FOR A TABLE.

Application filed June 25, 1927. Serial No. 22,562. Term of patent 3½ years.

To all whom it may concern:

Be it known that I, AARON S. KATZ, a citizen of the United States, residing at the city, county, and State of New York, have invented a new, original, and ornamental Design for a Table, of which the following is a specification, reference being had to the accompanying drawing, forming part thereof.

The figure is a perspective view of a table, showing my new design.

I claim:

The ornamental design for a table, as shown.
